Charles W. Pennington, Union, N. J.

Application March 18, 1952, Serial No. 18,950

Term of patent 14 years

(Cl. D86—10)

To all whom it may concern:

Be it known that I, Charles W. Pennington, a citizen of the United States of America, and a resident of Union, county of Union, and State of New Jersey, have invented a new, original, and ornamental Design for a Combined Brush and Shoehorn, of which the following is a specification, reference being had to the accompanying drawing, forming a part thereof:

Figure 1 is a top plan view of a combined brush and shoehorn embodying my new design;

Figure 2 is a side elevational view;

Figure 3 is a bottom plan view;

Figures 4 and 5 are opposite end views thereof, and

Figure 6 is an enlarged perspective view thereof.

I claim:

The ornamental design for a combined brush and shoehorn, as shown.

CHARLES W. PENNINGTON.
